[57] CLAIM

The ornamental design for a case for a disc cartridge, as shown and described.

DESCRIPTION

FIG. 1 is a perspective view of a case for a disc cartridge showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof;

FIG. 7 is a rear elevational view thereof; and,

FIG. 8 is a perspective view thereof; similar to FIG. 1 wherein the discs shown in broken lines are for illustrative purpose only and forms no part of the claimed design.
